LOUVER FOR AIR CONDITIONING SYSTEMS OR THE LIKE

Robert H. Bishop, 808 W. Park St., Champaign, Ill.

Filed Oct. 4, 1961, Ser. No. 66,973

Term of patent 14 years

(Cl. D62—4)

Fig. 1.

Fig. 2.

FIGURE 1 is a front elevational view of a louver for air conditioning systems or the like showing my new design;

FIGURE 2 is a rear elevational view thereof;

FIGURE 3 is a fragmentary prospective view showing the front and side of my Louver for air conditioning systems or the like design, and

FIGURE 4 is a top plan view thereof.

The dominant features of my design reside in the portions shown in full lines. The center of the louver in FIGS. 1 2, and 4, has been broken away to indicate an article of indeterminate length.

I claim:

The ornamental design for a louver for air conditioning systems or the like, as shown and described.
